UNITED STATES PATENT OFFICE.

ROSE SAHLIN, OF CHICAGO, ILLINOIS.

DESIGN FOR A WAIST-FRONT DISTENDER.

SPECIFICATION forming part of Design No. 29,098, dated July 26, 1898.

Application filed May 14, 1898. Serial No. 680,750. Term of patent 3½ years.

To all whom it may concern:

Be it known that I, ROSE SAHLIN, a citizen of the United States, residing at Chicago, county of Cook, and State of Illinois, have invented and produced a new and original Design for a Waist-Front Distender, which is fully set forth in the following specification, reference being had to the accompanying drawings, forming a part thereof.

This invention is designed for an article of ladies' wear of the class of garment-distenders, and specifically it is a design for a device to distend or maintain a puffed or inflated appearance in the waist portion of an outer garment above the belt or waistband line at the front.

In the drawings, Figure 1 is a side elevation of a waist-distender of my design. Fig. 2 is a front elevation, and Fig. 3 is a plan, of the same.

This design is characterized chiefly by the vertical outline as seen in side elevation of the single unitary swell A, which involves substantially the entire article. This outline comprises a curve whose apex or most prominent point is considerably above the middle point of the vertical dimension of the article, as indicated by the line X X. From this point downward the curvature diminishes gradually until it merges at y in a tangent sloping inward, to which tangential line the outline conforms until a point (indicated at y') at a very little distance above the waistline is reached, and from this point to the waistband the outline presents a curve slightly concave forward. From the crest at

the line X X upward the outline presents a curve continuous with the curve downward from that point and about equally convex through an arc of approximately sixty degrees, and from that point the curve flattens or straightens, the outline continuing to the upper edge very nearly in a direction tangent to the curve, the entire length of such straight or tangential portion being very much less than the straight or tangential portion of the lower outline, the whole effect being to make the upper portion appear much more abrupt in curvature than the lower, the lower being as a whole quite gradual, as illustrated.

The upper edge is slightly curved convexly upward at the middle portion a and merges in the two lateral edges by quite abrupt downward slopes a' a'. The lateral edges are completed by the slopes a² a², leading from the lower end upward and outward to the terminals a³ a³, in which the two slopes a' a² meet.

The characteristic of my design is the said single unitary swell A, involving substantially the entire article and having a vertical curvature, as seen in side elevation, substantially as shown and above described.

I claim—

The design for a waist-front distender herein shown and described.

In testimony whereof I have hereunto set my hand, in the presence of two witnesses, at Chicago, Illinois, this 11th day of May, 1898.

ROSE SAHLIN.
